UNITED STATES PATENT OFFICE.

FREDERICK L. ELLIS, OF MILLDALE, CONNECTICUT.

DOOR-BELL.

No. 833,450.

Specification of Letters Patent.

Patented Oct. 16, 1906.

Application filed January 25, 1905. Serial No. 242,660.

To all whom it may concern:

Be it known that I, FREDERICK L. ELLIS, a citizen of the United States, and a resident of Milldale, in the county of Hartford and State 5 of Connecticut, have invented certain new and useful Improvements in Door-Bells, of which the following is a specification.

My invention relates to improvements in door-bells; and the object of my invention is 10 to construct a bell with its mechanism so grouped about the center of the bell that but few parts are required for operating it.

With this end in view the invention consists in the novel construction and combination of parts, as will be hereinafter more particularly described, and specifically pointed out in the claims.

To enable others to understand my invention, reference is had to the accompanying 20 drawings, in which—

Figure 1 represents a central sectional view of the bell, flanged base-plate, escutcheon, and broken sectional view of the one end of the push-rod. Fig. 2 is an interior plan view 25 of the base-plate and operative mechanism with the bell removed. Fig. 3 is a detail view of the reverse side of the escapement-wheel, sectional view of the push-rod, extreme lower end of one of the arms of the 30 bell-crank lever that actuates the escapement-wheel, also broken view of the bridge in which said wheel is journaled. Fig. 4 is a modified detail construction of the escapement-wheel. Fig. 5 is a detail upper plan view 35 of the supporting-bridge. Fig. 6 is a detail plan view of a metal blank of which the bell-supporting post is formed. Fig. 7 is a detail view of the bell-supporting post. Fig. 8 is a detail side elevation of the escapement-wheel. 40 Fig. 9 is a detail side elevation of the bridge.

The construction and operation are as follows:

1 represents a section of the door to which the metal base-plate 2 is secured. 45 3 is a bridge having the feet 3^a secured to a recessed portion of the base-plate by the screws 4.

5 is the bell-supporting post, which I have shown, Fig. 6, as made of a single piece of 50 sheet metal, although it could be made solid, if so desired. The wings 5^a are folded over upon the body portion of the blank, with the holes 6, 7, and 8 alining with each other to furnish sufficient stock for threading to engage the threaded stem 9 of the bell 10. 55 (Shown at Fig. 1.) The wing 5^b is bent

around (see also Figs. 1 and 7) to form a support for the bell-crank lever 11. The ends of the legs 5^c of said post are provided with the tenons 12, adapted to be secured in the 60 elongated holes 13 of the bridge 3. (Shown at Fig. 5.)

The bell-crank lever 11 has the arms 14 and 15. The former, or longer arm, extends down through the elongated slot 16, Fig. 5, 65 of the bridge 3 and engages with the sides of the angularly-arranged slot 17 of the escapement-wheel 17^a (shown at Fig. 3) for the purpose of actuating said wheel in the manner presently to be described.

18 is the push-rod, passing freely through the door 1, hole 19 of the base-plate 2, hole 20 of the bridge, and curved slot 21 of the escapement-wheel, the enlarged portion 18^a of said rod normally resting on the upper surface of the bridge. The end of the arm 15 of the bell-crank lever will rest on top of said enlarged portion of said push-rod. 70

22 is an escutcheon on the outside of the door and carries the push-button 23, with 80 the forward end of its push-wire 24 freely engaging with a hole in the end of the push-rod, as shown at Fig. 1.

The escapement-wheel is located between the under side of the bridge 3 and the base-plate 2, with its shaft 25 journaled in the central hole 26 of the base-plate (shown at Fig. 1) and the hole 27 of the bridge 3. (Shown at Fig. 5.) The pallet 28 of the escapement-wheel is also journaled in a hole (not shown) 90 in the base-plate 2 and the hole 30 of the bridge 3. (Shown at Fig. 5.) 31 is the striking-hammer carried by said pallet.

32 is a retractile spring attached to the arm 14 of the bell-crank lever and is adapted 95 to secure positive engagement of the other arm of said lever with the push-rod and also to maintain said rod in its normal position.

Actuating the push-rod 18 through the medium of the button 23 will actuate the 100 bell-crank lever and rotate the escapement-wheel in the direction of the arrows. This partial rotary movement of said wheel in one direction, combined with its return movement caused by the spring 32, will agitate 105 the pallet 28 and cause the hammer to deliver a rapid succession of blows on the bell. The normal position of the escapement-wheel is established by the engagement of the push-rod with that end of the curved slot 21 which 110 is farthest from the lower end of the arm 15 of the bell-crank lever.

As previously stated, the object of my invention is to construct a bell with as little mechanism and as few moving parts as possible. To do this effectively, I have located 5 the escapement-wheel and bell-supporting post in axial alinement with the center of the bell, so that all intermediate mechanism for operating this wheel is done away with. Compactness of structure is further secured 10 by extending the push-rod through the escapement-wheel, and thus enable it to be brought closer to the central construction of the bell. In other words, the push-rod occupies a position inside of the circle described 15 by the teeth of the escapement-wheel and operates at right angles to said wheel. Centralizing the escapement-wheel enables it to be directly operated by a bell-crank lever pivotally supported on the bell-supporting 20 post, which further simplifies the general construction.

It is not necessary that the teeth of the escapement-wheel extend entirely around its periphery, as it need contain only a sufficient 25 number of teeth to secure the desired result. This is illustrated in the modified construction shown at Fig. 4. This construction enables the push-rod to occupy the same relative position with respect to the center of 30 said wheel as shown in the other views. In Fig. 4 the greater portion of the wheel is cut away, forming a toothed segment. The shoulder *a* will serve the same purpose of establishing the normal position of the wheel 35 as one end of the curved slot 21, before referred to.

Having thus described my invention, what I claim as new, and desire to secure by Letters Patent, is—

40 1. In a door-bell of the character described, a base-plate, a bridge secured thereto, a post secured to said bridge, a bell secured to and mounted on said post, an escapement-wheel journaled in said bridge and

base-plate and located between the same and 45 in axial alinement with the center of the bell, a bell-crank lever pivotally supported on the bell-post, a push-rod projecting through and operatively located within the circumference 50 of the escapement-wheel, for the purpose set forth.

2. In a bell of the character described, an escapement-wheel axially located with respect to the center of the bell, a support for the bell, a push-rod operatively located with 55 in the periphery of said wheel, a double-arm lever pivotally supported on the bell-support, one arm adapted to be engaged by said rod, the other arm engaging the escapement-wheel so that, through the medium of said 60 push-rod and lever, the escapement-wheel is rotated in one direction, a spring to return said wheel to its normal position, for the purpose set forth.

3. In combination, a base-plate, a bridge 65 secured thereto, an escapement-wheel journaled in said plate and bridge and located between the two, a hammer-carrying pallet engaging said wheel, a bell-supporting post made of a single piece of sheet metal and secured to said bridge, a bell mounted thereon, said bell and escapement-wheel in axial alinement with each other, a bell-crank lever pivotally supported on the bell-supporting post, a push-rod operatively located inside of 70 the periphery of the escapement-wheel and adapted to engage one arm of the bell-crank lever and thus actuate said wheel through the medium of the other arm of said lever, a 75 spring to bring all of the moving parts to a 80 normal position, for the purpose set forth.

Signed at Milldale, in the county of Hartford and State of Connecticut, this 7th day of January, A. D. 1905.

FREDERICK L. ELLIS.
